United States Patent Office

Des. 210,796
Patented Apr. 16, 1968

210,796

SELF-STANDING FLOOR LAMP

Dennis L. Jones, Coral Gables, Fla., assignor to Meyer Products, Inc., Cleveland, Ohio, a corporation of Ohio

Filed Sept. 26, 1967, Ser. No. 8,745

Term of patent 14 years

(Cl. D48—20)

FIG. 1

FIG. 2

FIGURE 1 is a side elevation of a self-standing floor lamp embodying my inventive design; and,
FIGURE 2 is a top plan view thereof.

I claim:

The ornamental design for a self-standing floor lamp, substantially as shown and described.

References Cited

UNITED STATES PATENTS

D 181,554 11/1957 Stiffel ----- D48—20
D 186,547 11/1959 Burton ----- D48—31

OTHER REFERENCES

Lamp Journal, July 1960, p. 54, pole lamp at lower right of page (copy in floor lamp box A-24).

Lightolier Catalog, rec'd Apr. 21, 1953, p. 9, 9835 lamp at center of page (copy in table lamp box A-17).

WALLACE R. BURKE, Primary Examiner.

WILLIAM C. WATSON, Assistant Examiner.